US0D1087992S

(12) United States Design Patent (10) Patent No.: US D1,087,992 S
Bullock et al. (45) Date of Patent: * Aug. 12, 2025

(54) DISPLAY SCREEN OR PORTION THEREOF WITH GRAPHICAL USER INTERFACE

(71) Applicant: Walmart Apollo, LLC, Bentonville, AR (US)

(72) Inventors: Adam Bullock, Bend, OR (US); Alexandra Saunders, Beaverton, OR (US); Sangeetha Santhanam, Irvine, CA (US); Helen Jordan, Oakland, CA (US); Caitlin Browne, Petaluma, CA (US)

(73) Assignee: Walmart Apollo, LLC, Bentonville, AR (US)

() Term: 15 Years

(21) Appl. No.: 29/899,044

(22) Filed: Aug. 3, 2023

(51) LOC (15) Cl. 14-04

(52) U.S. Cl.

USPC D14/485

(57) CLAIM

The ornamental design for a display screen or portion thereof with graphical user interface as shown and described.

DESCRIPTION

The FIGURE is a front view of a display screen or portion thereof with graphical user interface showing our new design.

The peripheral dash-dot-dash lines illustrate a display screen or portion thereof and forms no part of the claimed design. The remaining broken lines within the peripheral dash-dot-dash lines illustrate portions of the graphical user interface which form no part of the claimed design.

1 Claim, 1 Drawing Sheet
